UNITED STATES PATENT OFFICE.

HANS P. HANSON, OF CAMBRIDGE, MINNESOTA.

HEATING APPARATUS.

Application filed January 21, 1926. Serial No. 82,684.

This invention relates to auxiliary heating apparatus adapted to derive its source of heat from the outlet flue of a furnace, stove or other heating plant.

5 It is an object of this invention to provide extremely simple but highly efficient apparatus for conserving a large proportion of otherwise wasted heat passing through the flue and chimney of the ordinary heating plant.

10 It is a further object to direct the smoke from a heating plant through a tortuous passageway enclosed within an open bottom casing, the top of said casing communicating 15 with heat registers whereby an auxiliary current of clean air will be set up through said casing and will be heated by the radiation from said tortuous passageway, thereby setting up said auxiliary current of heated 20 air.

More specifically it is an object of the invention to provide an inner closed casing communicating with the outlet flue of a heating plant and centrally divided to form two 25 compartments connected at their lower ends through an opening in the partition and an outer casing opened at its bottom end and superimposed about and spaced from the inner casing whereby an auxiliary current of 30 air will be set up through said outer casing and heated by the passage of hot smoke through the inner casing.

A still further object of the invention is to provide inner and outer casings formed 35 from a plurality of sheet metal walls adapted to be readily assembled or disassembled and capable of being collapsed in compact form for shipping.

An additional object is to support the outer 40 casing in spaced relation about the inner casing in a novel and highly efficient manner.

These and other objects of the invention will be apparent from the following description made in connection with the accompanying 45 drawings wherein like characters refer to similar parts throughout the several views and in which

Figure 1 is a somewhat diagrammatical view showing the auxiliary heating apparatus interposed between the flue of a furnace and a chimney;

Figure 2 is a perspective view of the heating apparatus, some portions being broken away to show the interior thereof;

50 Figure 3 is a plan view with some portions broken away and others shown in section;

Figure 4 is a vertical section taken on the line 4—4 of Figure 3, and

Figure 5 is a cross section taken on the line 5—5 of Figure 4.

In the drawings a furnace of any standard type is indicated by the letter A and a chimney or stack by the letter B. The ordinary flue or smoke pipe from the furnace is indicated by the letter C.

The auxiliary heating apparatus is interposed between the flue C and the chimney B and comprises inner and outer upright rectangular casings indicated as entireties by the letters D and E. Inner casing D is closed at top and bottom and is made up of vertical walls formed by a plurality of independent channel members 6, having outturned flanges 6^a extending at 45 degree angles to the bodies thereof. The bottom 7 of casing D is flanged and secured to the lower edges of the walls 6.

A top 8 closes the upper end of casing D provided with flanges adapted to be secured or inset within the walls 6. A vertical partition 9 extends through casing D diagonally dividing the space within into two compartments, the vertical sides thereof extending between two pairs of vertical flanges 6^a and projected a considerable distance beyond the outer vertical corners of said inner casing.

A relatively large recess 9^a formed in the lower portion of partition 9 connects the two compartments formed in casing D by said partition. A hinged door 10 closes an opening at the lower end of one side of 90 casing D permitting access to the bottom of said casing for cleaning purposes. Outer casing E is superimposed about and spaced from inner casing D, and is constructed for the most part similar to said inner casing,

95 the vertical walls 11 being provided with flanges 11^a secured together in rectangular arrangement by a plurality of vertically spaced bolts 12. The projecting sides of partition 9 extend between opposite pairs of 100 flanges 11^a and are secured thereto, bolts 12 passing through said projecting edges.

In practice, packing strips (not shown) will be inserted between the several flanges 11^a of the outer casing at their joints and the flanges 6^a of the inner casing. The walls of the outer casing may also be insulated with an asbestos coating to raise the efficiency of the device.

105 From the above description it will be seen that the outer casing E is supported in spaced relation to the inner casing by means

of the vertical partition. It will also be noticed that the lower end of casing E is open and spaced some distance above the bottom of casing D. A cover 13 fits over 5 the top of casing E having downwardly extended flanges 13^a secured to the upper edges of vertical walls 11. The furnace flue C passes through a fitting 11^b in one of the vertical walls 11 and communicates with 10 one of the compartments formed in inner casing D through the top portion of one of the vertical walls 6. A conduit 14 likewise passes through one of the vertical walls 11 of outer casing E communicating with the 15 opposite compartment of inner casing D through either one of its vertical walls 6. Conduit 14 is connected to chimney or stack B as shown in Figure 1.

A conduit 15 communicates with the top 20 of outer casing E and delivers to a desired register 16 located in the wall or floor of a room. If desired, of course, conduit 15 may be dispensed with and the room in which the apparatus is disposed will then be heated 25 by the auxiliary current of air.

Operation.

While the operation may be obvious from the foregoing description in connection with 30 the drawings, the same may be briefly summarized as follows:

The hot smoke will be delivered from the furnace A through the flue C into one of the compartments of inner casing D. This 35 current of hot smoke will pass downwardly through the recess in partition 9 and upwardly through the opposite vertical compartment and out of inner casing D through conduit 14 and through the chimney or stack B. The effect of inner casing D is similar to that of a depending elbow in a flue and does not in any way effect the draft from the chimney or stack. Inner 40 casing D is constructed of sheet metal or some other heat conducting material and obviously has a large amount of radiating 45 surface, the cross sectional area of each of the compartments formed by the vertical partition being approximately 1½ times as great as the cross sectional area of the delivery flue of the heating plant. This construction permits a large amount of heat to 50 be radiated within the outer casing E.

This heat will cause an auxiliary current 55 of air to be set up through the outer casing, said air entering outer casing E through the open bottom thereof and passing upwardly about the outer sides of casing D and through the top 13 into conduit 15 where 60 said heated current of clean air may be delivered for heating the rooms of the building.

The walls of outer casing E may be covered 65 with asbestos or other non-conducting material to increase the efficiency of the

plant. While the auxiliary current of heated air may be delivered directly in the room in which the heating apparatus is disposed, the device is especially adapted to heat rooms on the floor above the furnace, stove 70 or heating plant.

It will be obvious that the device may be readily assembled or disassembled and since the respective casings are constructed of a plurality of flat sheet metal plates the device 75 may be disassembled and the several sheets stacked to form a very compact rectangular bundle for shipping. It will also be noted that in assembling the device the walls 11 and outer casing E may be set up to permit so the conduit 14 to extend at right angles to the outlet flue C or in alignment therewith. In other words, due to the fact that inner casing D is centrally and diagonally divided by partition 9 the outlet from the proper 85 compartment may be made through either of the two adjacent walls 6 dividing said compartment. In assembling the device this fact must be borne in mind and the walls of casings E and D respectively equipped 90 with the apertures and the fittings for the conduit 14 will be set up on the side of the device facing the chimney or stack B.

As has been described, the partition 9 not only diagonally divides the inner casing D 95 to form two communicating compartments, but also furnishes efficient means for mounting the outer casing E in spaced relation about said inner casing.

The device has been put to extensive actual use and has been found highly efficient for the purposes enumerated. It has been found that in a two-story building or house a furnace of sufficient capacity to merely heat the lower floor thereof, sufficient heat 105 may be obtained from the outlet flue by the employment of applicant's device to efficiently heat the rooms on the upper floor.

From the above description it will be seen that applicant has invented simple heating 110 apparatus of high efficiency capable of being manufactured at little cost and comprising few parts.

It will of course be understood that various changes may be made in the form, details, proportions and arrangement of parts 115 without departing from the scope of the invention.

What is claimed is:

1. Heating apparatus having in combination a closed inner casing of heat conductive material, a longitudinally disposed partition therein dividing said casing into communicating compartments, longitudinal flanges extending outwardly from said casing, means for connecting the outlet flue of a heating plant with one of said compartments, and discharge means connected with said other compartment, an outer casing surrounding said inner casing and secured to 120
2. Heating apparatus having in combination a closed inner casing of heat conductive material, a longitudinally disposed partition therein dividing said casing into communicating compartments, longitudinal flanges extending outwardly from said casing, means for connecting the outlet flue of a heating plant with one of said compartments, and discharge means connected with said other compartment, an outer casing surrounding said inner casing and secured to 125
3. Heating apparatus having in combination a closed inner casing of heat conductive material, a longitudinally disposed partition therein dividing said casing into communicating compartments, longitudinal flanges extending outwardly from said casing, means for connecting the outlet flue of a heating plant with one of said compartments, and discharge means connected with said other compartment, an outer casing surrounding said inner casing and secured to 130

said longitudinal flanges in spaced relation to said inner casing, said outer casing having an intake passage adjacent the lower end thereof, and a discharge passage adjacent the upper end thereof.

2. Auxiliary heating apparatus having in combination a closed inner casing formed from a pair of shell sections having registering flanges, a partition dividing said casing into two compartments communicating at their lower ends, said partition having its sides extending between said registering flanges of said shell sections and projecting therebeyond, means for connecting one of said compartments with the outlet flue of a heating plant, discharge means communicating with said other compartment, an outer relatively large casing enclosing said inner casing, and secured in spaced relation thereto by means of the outwardly projecting sides of said partition, said outer casing having air intake means adjacent the lower end thereof, and discharge means adjacent the upper end thereof.

3. Auxiliary heating apparatus having in combination an upright closed inner casing constructed of heat conductive material, a partition dividing said casing into two compartments communicating at their lower ends, said partition having its sides extending through the walls of said casing and projecting therebeyond, means for connecting one of said compartments with the outlet flue of a heating plant and means for connecting the other of said compartments with a chimney or stack, an outer open-bottomed casing superimposed about said inner casing and supported in spaced relation thereto by means of the outwardly projecting sides of said partition, and heat delivery

means communicating with said outer casing.

4. Auxiliary heating apparatus having in combination an upright closed inner casing of heat conductive material comprising a plurality of vertical walls secured together, a vertical partition dividing said casing into two communicating compartments and having its vertical sides extending between the joints of said vertical walls and projecting therebeyond, an open-bottomed outer casing also comprising a plurality of vertical walls secured together and supported in spaced relation to said inner casing by means of the projecting edges of said partition and heat delivery means communicating with said outer casing.

5. Auxiliary heating apparatus having in combination a closed upright inner casing comprising a plurality of flat walls provided with upturned vertical flanges, a vertical partition diagonally dividing said casing into a pair of communicating compartments and having its vertical sides extending between two pairs of adjacent vertical flanges of said walls, means for securing said flanges and partition together, means for connecting one of said compartments with the outlet flue of a heating plant and means for connecting the other of said compartments with a chimney or stack, an outer open-bottomed casing comprising a plurality of flat walls having outturned vertical flanges, means for securing said flanges together and to the edges of said vertical partition to support said outer casing in spaced relation to said inner casing, and heat delivery means communicating with said outer casing.

In testimony whereof I affix my signature.

HANS P. HANSON.
